US0D1019381S

(12) **United States Design Patent** (10) **Patent No.:** **US D1,019,381 S**
(45) **Date of Patent:** **** Mar. 26, 2024**

(54) **PHARMACEUTICAL PACKAGE**

(71) Applicant: **Gilead Sciences, Inc.**, Foster City, CA (US)

(72) Inventors: **Benjamin Luke Kozub**, San Francisco, CA (US); **Brian Nilsoft**, San Carlos, CA (US); **Kevin Nguyen**, San Francisco, CA (US); **James Paul Oberhauser**, Saratoga, CA (US); **Roman Shumylo**, Dublin, CA (US); **Joseph Anthony Cordova**, Stockton, CA (US); **Jinhui Yun**, San Francisco, CA (US); **William Harold Lizor, Jr.**, San Mateo, CA (US); **Adam Hilborn**, Brooklyn, NY (US); **Jesse Arnold Fourt**, Menlo Park, CA (US); **Léo Boris Marzolf**, San Francisco, CA (US); **Pratap Uday Ganapathy**, Menlo Park, CA (US); **Brooke Genelle Thyng**, San Francisco, CA (US); **Caricia Catalani**, San Francisco, CA (US); **Soizic Porhel**, Amsterdam (NL); **Jose Angel Meza**, San Francisco, CA (US); **Steven M. Scally**, Cherry Hill, CO (US); **Mary Cassandra Lodwick**, Brooklyn, NY (US)

(73) Assignee: **GILEAD SCIENCES, INC.**, Foster City, CA (US)

(**) Term: **15 Years**

(21) Appl. No.: **29/842,573**

(22) Filed: **Jun. 14, 2022**

(57) **CLAIM**

The ornamental design for a pharmaceutical package, as shown and described.

DESCRIPTION

FIG. 1 is a front perspective view of a pharmaceutical package in an open configuration;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

(Continued)

FIG. 9 is a front perspective view of the pharmaceutical package in a partially-folded configuration;
 FIG. 10 is a back perspective view thereof;
 FIG. 11 is a front view thereof;
 FIG. 12 is a back view thereof;
 FIG. 13 is a left side view thereof;
 FIG. 14 is a right side view thereof;
 FIG. 15 is a top view thereof;
 FIG. 16 is a bottom view thereof;
 FIG. 17 is a front perspective view of the pharmaceutical package in a folded configuration;
 FIG. 18 is a back perspective view thereof;
 FIG. 19 is a front view thereof;
 FIG. 20 is a back view thereof;
 FIG. 21 is a left side view thereof;
 FIG. 22 is a right side view thereof;
 FIG. 23 is a top view thereof; and,
 FIG. 24 is a bottom view thereof.

The broken lines, the areas within them, and the unshaded areas bounded by both broken lines and solid lines depict portions of the pharmaceutical package that form no part of the claimed design.

1 Claim, 15 Drawing Sheets
